UNITED STATES PATENT OFFICE.

ALMON E. NORRIS, OF CAMBRIDGE, MASSACHUSETTS.

HOISTING APPARATUS.

1,027,884.

Specification of Letters Patent.

Patented May 28, 1912.

Application filed January 14, 1905. Serial No. 241,071.

To all whom it may concern:

Be it known that I, ALMON E. NORRIS, a citizen of the United States, residing at Cambridge, in the county of Middlesex and State of Massachusetts, have invented an Improvement in Hoisting Apparatus, (Case A,) of which the following description, in connection with the accompanying drawings, is a specification, like letters on the drawings representing like parts.

My invention consists in improvements in hoisting apparatus; being particularly concerned with the control and operation of load-lifting and load-carrying devices.

My invention will be best understood by reference to the following specification when taken in connection with the accompanying drawings, showing one specific embodiment thereof, while its scope will be more particularly pointed out in the appended claims.

In the drawings,—Figure 1 shows in plan the two drums of a double drum hoisting engine in which is embodied one form of my invention; Fig. 2 is a side elevation of the same; Fig. 3 is an elevation partially in section, of one of the hoisting drums shown in Fig. 1; Fig. 4 is a similar view of the other of the two drums; Fig. 5 is a similar view of a modified form of my invention; Fig. 6 shows diagrammatically the arrangement of the controlling ropes in one system to which my invention may be applied; and, Fig. 7 is a detail of the trolley carriage represented in Fig. 6.

Referring to Figs. 1 to 4, inclusive, the rope winding drums *a* and *b* are rotatably mounted upon the respective drum shafts *a'* and *b'*. Upon the drum shafts are fixedly secured the intermeshing gears *a²* and *b²*, so that, in the particular arrangement herein shown, the movement of shaft *a'* in one direction, is accompanied by a corresponding movement of the shaft *b'* in the opposite direction. Any suitable or appropriate means for transmitting driving movement to one or the other of the two shafts may be employed; such, for example, as the driving pinion *c* shown partially broken away in Fig. 1 and connected to be driven by any suitable motor (not shown); or the motive means, whether steam, electric or otherwise, may be directly connected to one of the said drum shafts.

In order that the two drums may each

be driven by and with its respective shaft when desired, I have provided clutching means, such clutching means herein being frictional. In respect to the clutching means, the two drums are substantially the same and reference is had to Fig. 3, where I have shown secured to and carried by the inner face of the gear *a²* suitable conical friction blocks *d*, adapted to frictionally engage suitably-shaped surfaces upon the flange of the drum *a*, when the latter is moved lengthwise the shaft *a'*, thereby to drive the said drum directly and with the speed of the shaft *a'*.

Any suitable clutch operating means for forcing the drum into engagement with the friction clutch may be employed, and I have here shown one construction which is particularly advantageous in connection with the invention as hereinafter described.

At the opposite end of the drum from the gear *a²* and bearing against the drum hub, is a collar *e*, against which presses a sliding cross key *e'*, the latter being engaged by the sliding and axially arranged rod *e²*. Bearing against the rod is the end of the operating screw *e⁴*, which may be turned by means of the hand lever *e⁵* (Figs. 1 and 2), thereby acting to force the rod *e²* and the pin *e'* toward and against the collar *e* to compel frictional engagement between the winding drum and the gear. On reverse movement of the said lever disengagement of the clutch is insured through the action of the spring *e⁶*.

The drum *a* may be directly clutched to the shaft, as described, or may be driven, when desired, in the same direction but at a slower speed by means of planetary gearing, as follows: Keyed or otherwise secured to the shaft *a'* to rotate therewith, is the pinion *f* engaging with one or more intermediate pinions *f'*, the latter journaled upon and carried by the drum *a*. The pinion or pinions *f'* are in engagement with an internal gear *f²*, formed upon or carried by a rotary member *f³*, the latter being journaled to rotate about the shaft *a'*. The rotary member *f³* is encircled by the brake band *f⁴*, which may be tightened to clasp a suitable brake surface upon the face of the said rotary member; thereby acting to oppose or stop rotary movement thereof. When the brake band is loosened, the member *f³* is free for rotation and the pinion *f* exerts no effect.

upon the winding drum. When the band is tightened, and the member f^3 held stationary, the drum a is caused to revolve with the shaft a' but at a reduced speed.

5 Referring to Fig. 4, the drum b is provided with a speed-reduction gearing similar to that already described, but reversely arranged, so that when said gearing is thrown in by tightening the brake band, 10 said drum is caused to revolve at a reduced speed but in the opposite direction to the shaft b' . As in the case of the drum a , a pinion g is provided, keyed to the shaft b' and engaging one or more intermediate pinions g' ; the latter being likewise in engagement with an internal gear g^2 . Here, however, the pinion g' is journaled upon and carried by the rotary member g^3 ; and the internal gear g^2 is formed upon or secured 15 to the drum itself. With this relation of the gears, when the rotary member g^3 is held by the brake band g^4 , the movement of the winding drum is the reverse of that of the shaft b' . It will thus be seen that by means 20 of the controlling levers which tighten the brake bands and the friction clutches, and which, as is usual in this class of apparatus will be arranged within convenient reach of the operator, said drums may be clutched to 25 the shaft either together or independently for direct drive, or driven through the planetary reduction gearing at a relatively lower speed and with a reversal of the relative movements of the two drums.

30 In Fig. 5 I have shown a different form of drum corresponding to the drum a but which is capable of substantially the same movements. Instead of clutching the gear a^2 directly to the drum a , the said gear is 35 clutched to the rotary member f^3 , which herein is provided with friction surfaces adapted for that purpose and is located between the drum and the gear. This causes 40 an interlocking of the planetary gearing and compels the drum a to move with the said gear. When unclutched, the friction band f^4 may be tightened in the usual way 45 to cause a slower movement of the winding drum. Obviously, a drum similar to drum 50 b may also be constructed upon the plan shown in Fig. 5. In Fig. 5 I have also shown a different form of clutch operating device. The gear a^2 is fixedly secured to the shaft a' and the latter is provided at its 55 opposite end with a collar e^{6x} bearing against which is a sleeve e^7 , which may be forced outward from the stationary abutment e^8 by the twin operating screws e^9 ; the latter being turned by suitable links and levers (not herein shown) but similar to those shown in my reissued Patent No. 12,985. When said 60 screws are turned to force the sleeve outward from the abutment, the sleeve e^7 engages with the collar e^{6x} and draws the entire shaft with the attached gear a^2 in the

same direction, forcing the friction members of the clutch into clutching engagement. With either the clutch-operating device shown in Fig. 5 or that shown in Fig. 3, the operating member or members are located outside of the journal or abutment e^8 of the engine frame and I am enabled to bring the drum close to the said abutment; this being of particular advantage with the construction of drum shown in Figs. 3 and 4, where the strain which is introduced by the friction band f^4 may be brought nearly into line with the said journal or abutment. This feature is a point which gives preference to the drum construction shown in Fig. 3. It is to be observed that in the construction exhibited by Fig. 5 the friction blocks engage the more slowly rotating rotary member f^3 so that the force required for holding the friction clutches in engagement is less with a pair of drums constructed as in Fig. 5 than as in Fig. 4.

In Fig. 6 I have outlined diagrammatically a hoisting system to which my invention as described may be usefully applied. 90 This comprises a cable or trackway system along which is adapted to run a trolley h carrying a suitable load-lifting device, such as the clamshell bucket or grab v . The rope winding drums are represented diagrammatically at a and b and from these the ropes k and l respectively lead to the trolley carriage approaching the latter from opposite directions. The rope k which after passing 95 over guide sheave k' upon the trolley passes around and about sheaves v' and v^3 on the grab, and thence to the trolley to which it is secured. The rope l passes about a guide sheave h^2 upon the trolley, thence about the sheave v^3 upon the grab and thence to the 100 trolley, to which it is secured. The grab illustrated is of an ordinary, well-known construction. When both ropes are lengthened, the grab is lowered and when the ropes are shortened, the grab is raised. 105 When one is lengthened relatively to the other, the jaws of the grab are opened or closed. The trolley is controlled and maintained as desired in any fixed position by the endless controlling rope m attached thereto 110 and passing about the drum n adjacent the drums a and b ; the said drum n having applied thereto a foot-brake (not shown) under the control of the operator.

With the drums a and b constructed and 115 arranged as described, the operator is enabled to traverse the carriage with its attached load in either direction desired by releasing the drum n , throwing in the friction clutches and starting the driving motor in the required direction. This, as is evident, turns the drum to wind in one of the ropes l or k , while similarly unwinding the other, and, as will be seen from Fig. 6, this will cause the trolley to travel along 120

the cable or trackway at the highest speed of which the engine is capable without altering the elevation of the attached load. When, however, it is desired to hoist the load upon the trolley, the drums are unclutched from the shaft and the brake bands tightened to render effective the planetary gearing. This results in reversing the relative rotation of the drums, so that both drums may be turned to wind in both of the ropes *l* and *k* and raise the load but at a greatly reduced speed, thus rendering more effective the power of the driving motor.

In Figs. 6 and 7 I have shown an attachment for the trolley *h* adapted to engage and hold the grab when the latter is elevated. This consists in a pair of levers *o* and *o'* pivoted at *o²* and having jaws *o³*, the latter adapted to catch and hold the pin *o⁵* of the sheave *v³* upon the grab. The opposite ends of the levers are secured to links *o⁶* and *o⁷*, connected each to the roll *o⁸* to form a toggle joint. The two levers are slotted as shown at the point where the pivot *o²* passes through them, so that as the grab is lifted the pin *o⁵* pushes the levers upwardly and therefore apart to permit the pin to enter between them, after which they drop from their own weight and draw together, securing and holding both the pin and the grab. To release the grab the jaws must be drawn apart, and this is accomplished by lifting up the roll *o⁸*. In order that the roll *o⁸* may be lifted and the jaws spread to release the grab whenever desired by the operator at the hoisting engine, I provide a stationary rope or cable *p*, which passes over suitable guide sheaves on the trolley and beneath the roll *o⁸*, being fixedly secured at one end 40 of the track or cable way and at the opposite end to the bell crank lever *p'*, to which latter is attached the depending rope *p²*, secured to the lever *p³*. The latter may be moved at will by the operator to tighten on the rope *p* and thus raise the roll *o⁸* and release the grab.

While I have herein for illustrative purposes shown one form of my invention and with reference to one special application, it will be obvious that my invention may be applied in many other ways than that herein shown, and may be modified extensively without departing from the spirit thereof.

Claims.

55 1. A hoisting engine having a plurality of winding drums provided each with friction driving means, and also each with separate speed reduction driving means, and means for driving said drums through either of said driving means.

2. A hoisting engine having a pair of winding drums, driving means, friction members connected to be driven by said driving means, means for clutching said friction members to said drums, separate speed

reduction gearing for each of said drums and also connected to be driven by said driving means, and means for rendering effective said speed reduction gearing.

3. A hoisting engine having a pair of parallelly arranged winding drums, driving means, friction members connected to be driven by said driving means, gearing connecting said friction members, means for clutching said friction members to said drums, speed reduction gearing also connected to be driven by said driving means, and means for rendering effective said speed reduction gearing.

4. A hoisting and conveying machine 80 having a pair of drums, means for rotating the said drums at the same speed, and means for rotating them together at a different speed from said first speed and in a reverse relation one to the other.

5. A hoisting and conveying machine having a pair of drums, means for driving the same to cause the rope to wind on one and unwind from the other at the same rate of speed, and means for driving them at a 90 slower speed in reverse relation to cause the rope to wind on or unwind from each drum.

6. A hoisting and conveying machine having a plurality of drums provided each with a clutching device for direct drive at 95 relatively high speed and with speed reduction gearing for rotating said drums at a relatively slow rate of speed, said speed reduction gearing also providing for the change in the relative direction of rotation. 100

7. A hoisting and conveying machine having a pair of drums, driving means therefor, means to clutch said drums to said driving means, and planetary gearing transmission means also for said drums, the latter providing for a relatively reverse rotation at a slower speed.

8. A hoisting and conveying apparatus having a rope drum, driving means therefor, a clutch device for connecting said drum directly to said driving means, a driving pinion a member having a normally free rotation adjacent said drum, an internal gear, an intermediate pinion meshing with said driving pinion and said internal gearing, said intermediate pinion and said gear being the one carried by the drum and the other by said freely rotatable member, and means for opposing movement of said member.

9. A hoisting engine having driving means, a pair of drums provided each with a driving pinion, a member having normally a free rotation adjacent its drum, an internal gear, an intermediate pinion meshing with the driving pinion and the internal gear, said intermediate pinion and said gear being carried in one case by the freely rotatable member and the drum, respectively, and in the other, by the drum and the freely

rotatable member, respectively, means to oppose rotation of the freely rotatable member, and suitable clutching means for connecting the drums to the driving means.

5. 10. In an apparatus of the class described, a rope winding drum, a journal bearing for the same, a friction clutch device and one or more clutch operating screws working on the opposite side of said bearing from said drum and acting to draw the movable member of the clutching device toward the journal bearing.

10. 15. In an apparatus of the class described, a rope winding drum, a journal bearing for the same, a friction clutch device, planetary gearing also for driving said drum, including a rotatable member adjacent the bearing and means for holding the same and clutch operating means on the opposite side of said bearing from said drum and rotatable member.

15. 20. In an apparatus of the class described, a winding drum, a journal bearing for the same, a friction clutch device, said drum being between said bearing and said clutch device, a clutch operating member on the opposite side of said journal from said drum, and connections between said clutch device and said operating member passing through said bearing and said drum.

20. 25. A hoisting engine having driving means, a pair of drums provided each with a clutching device and means for clutching the same directly to the driving means, and means for giving at least one of said drums a reverse rotation at a reduced speed, the same comprising a toothed driving member connected to said driving means, a toothed member connected to said drums and an intermediate intermeshing toothed member normally freely rotatable, and suitable means to oppose rotation of said freely rotatable member.

25. 30. A hoisting engine having driving means, a pair of drums provided each with clutching devices for clutching the same directly to said driving means, and planetary gearing between said driving means and at least one of said drums for giving a reverse rotation of said drum at a reduced speed, while permitting independent movement of the other drum.

30. 35. A rope winding device having a driving shaft, a rope-winding drum thereon, a clutching device driven by said shaft and adapted to clutch the said rope-winding drum, and planetary gearing between said shaft and said drum, the same including the driving pinion fixed to said shaft, an internal gear secured to the drum, one or more intermediate pinions carried by a member rotatably mounted in the said driving shaft, and a band-brake for holding said member fixed or for leaving the same free to rotate, 65 whereby the said hoisting drum may be

clutched directly to the driving shaft or driven positively through the said planetary gearing at a reduced speed.

16. 70. A rope-winding device comprising a driving shaft, a rope-winding drum, clutching means for clutching said drum directly to said driving member, and planetary gearing between said member and said drum including a driving and a driven gear and an intermediate rotatably mounted gearing member, and means for holding the latter fixed to drive the drum at a reduced rate of speed.

17. 75. A hoisting engine having a pair of rope-winding drums mounted side by side, driving shafts therefor, driving means for said driving shafts, clutching devices in each of said drums to clutch the same directly to their respective driving shafts, planetary gearing means between said drums and their respective driving shafts, and means whereby the said drums may be driven at will through said planetary gearing each independently of the other.

18. 80. A hoisting engine having a pair of rope-winding drums, driving means, means for clutching each of said drums to be driven directly by the driving means, a planetary gearing connection for each of said drums, and means whereby the drum 95 may be driven each independently of the other through said planetary gearing means.

19. 85. A rope-winding device having a pair of rope-winding drums, means for driving said drums each in a given direction at the same rate of speed, and means for driving said drums in a changed relative direction at a reduced rate of speed.

20. 90. A hoisting engine having a plurality of winding drums provided each with friction driving means, and also with additional driving means for giving a definite but reduced speed to the winding drums, and means for driving said drums through either of said driving means.

21. 95. A hoisting engine having a pair of winding drums, driving means, friction members connected to be driven by said driving means, means for clutching said friction members to said drums, speed reduction gearing also connected to be driven by said driving means and to impart to said winding drums a definite but reduced rate of movement, and means for rendering effective said speed reduction gearing.

22. 100. A rope-winding device having driving means, a rope-winding drum, planetary gearing between said driving means and said drum, including a rotatable driving element, means for holding said driving element fixed to render said gearing effective, and a clutch for connecting said driving means and said rotatable element for direct drive of said rope-winding drum at a reduced speed.

23. A rope-winding device having a driving shaft, a rope-winding drum thereon, a clutching device driven by said shaft, planetary gearing between said shaft and said drum, the same including a pinion member, an internal gear member and one or more intermediate pinions carried by a rotatable member, one of said members being secured to the drum, another to the shaft and another freely rotatable about the shaft, means for holding said rotatable member fixed, and means also for causing clutching engagement between the same and the said clutching device.
24. The combination with the winding drum "a", the clutch "d", gearing members f, f', f^2, f^3 , and f^4 .
25. The combination with the winding drums "a" and "b" of the gearing members f, f', f^2, f^3 , and f^4 , and g', g^2, g^3 , and g^4 .
- In testimony whereof, I have signed my name to this specification, in the presence of two subscribing witnesses.

ALMON E. NORRIS.
